UNITED STATES PATENT OFFICE.

EMORY J. GODMAN, OF JERSEY CITY, NEW JERSEY, ASSIGNOR TO STERLING SEAL COMPANY, OF NEW YORK, N. Y., AND JERSEY CITY, NEW JERSEY. A CORPORATION OF MAINE.

MACHINE FOR SEALING BOTTLES.

No. 892,988.

Specification of Letters Patent.

Patented July 14, 1908.

Application filed September 27, 1907. Serial No. 394,778.

To all whom it may concern:

Be it known that I, EMORY J. GODMAN, of Jersey City, in the county of Hudson and State of New Jersey, have invented certain 5 Improvements in Machines for Sealing Bottles, of which the following is a specification.

This invention relates to certain improvements in what is generally known as the sealing head, or that part of the machine which 10 embodies the devices whereby a sealing cap is directly secured to a bottle head having thereon an annular shoulder, as will hereinafter fully appear. In the description of the 15 said invention which follows, reference is made to the accompanying drawings forming a part hereof, and in which,—

Figure 1 is an exterior side elevation of the improved bottle sealing machine. Fig. 2 is an enlarged partly sectional elevation of the 20 sealing head alone. Fig. 3 is an underside view of Fig. 2. Fig. 4 is a still further enlarged section of a part of Fig. 2. Fig. 5 is a perspective view of one of a system of cap-indenting bolts forming parts of the sealing 25 head.

Referring now to the drawing, 1 is the columnar stand of the machine, and 2 a vertically moving bar situated within the columnar stand. Due to a spring mechanism 30 (not shown) within the columnar stand, the bar 2 is held yieldingly at its highest point, as shown in Fig. 1. The sealing head is fastened to the upper end of the bar 2, as shown in Fig. 1, and it consists of a tubular block 3 having a bracket *a*, whereby it is attached 35 rigidly to the bar 2 by means of a nut. At the lower end and forming a part of the sealing head, is a guide *b* adapted in the up-and-down movement of the sealing head to slide 40 within a groove formed in a collar *c* clamped around the top of the columnar stand 1, as shown in Fig. 1.

5 is a treadle whereby downward motion of the bar 2, together with the sealing head, is effected. The means of attachment between the treadle and the bar 2 are not shown, for the reason that they form no part of the present invention.

The tubular block 3 is closed at its upper 50 end by a hollow screw cap *d*; and between the said cap and the end of the block is clamped an annular disk 7 to guide the stem 9 which terminates at its lower end in a hollow conical enlargement *e* the purpose of which will

hereinafter appear. The lower end of the tubular block 3 is also enlarged and bored to receive the annulus 10 which is held in place by an exteriorly threaded ring 12. The central opening in the annulus 10 is of tapering or conical form, and its angle of inclination corresponds substantially with that of the enlargement *e* of the stem 9 as shown in Figs. 2 and 4.

13 is a collar screwed upon the stem 9, adapted to fit loosely within the tubular block 3. This collar when in its lowest position rests upon the portion of the annulus 10 which projects inward and beyond the inner circumference or bore of the block 3; and extended between the said collar and the disk 7 is a spiral spring 15. The bottom of the enlargement *e* of the stem 9 is bored to form the cavity *f* which is of such a diameter and depth as will freely admit of the entrance thereto of a sealing cap, as shown in Fig. 4 wherein the cap is denoted by *A*; and within the said stem and supported by a pin *g* is a spring-held permanent magnet 17 (shown only in Fig. 2) the lower end of which, when in its lowest position, projects slightly beyond the surrounding surface of the said enlargement. The office of the magnet is to hold a sealing cap within the cavity *f* before the application of the cap to a bottle head.

19, 19 are bolts resting in radially disposed 85 holes which extend through the wall of the enlargement *e* of the stem 3 in an inclined position as shown in Figs. 2 and 4, and the said bolts are held with their ends or points flush with the conical inner surface of the cavity *f*, by means of springs *h*, as shown in Figs. 2 and 4. The bolts 19 are shown as of rectangular cross section and as having chisel points, but I do not confine myself to the use of bolts of any particular shape, as it is only 95 necessary that they should be adapted when forced inward, to properly indent the skirt of the sealing cap immediately below the shoulder of the bottle head in the sealing operation hereinafter described; nor do I limit myself to the employment of any particular description of springs *h*, and those illustrated in the drawing are of the plate order and notched at their ends to fit over the bolts which are grooved to receive them, as shown 100 particularly in Fig. 5. In vertical alinement with each of the bolts 19, the wall of the annulus is bored, and the holes *i* thereby

produced are inclined so as to be at right angle with the inner conical surface of the annulus, as shown in Figs. 2 and 4.

20, 20 are stems which occupy the holes 5 and are adapted to have a longitudinal movement therein, the said movement being limited in an outward direction by the heads *j*, and in an inward direction by the collars *k*; and between the collars *k* and plugs *m* are 10 placed the compressed spiral springs 21. The position of the stems when the machine is at rest is shown in Fig. 2, and their position during the sealing operation is represented in Fig. 4.

15 23 is an ordinary bottle seat, and 24 a rest whereby the bottle is centralized with respect to the sealing head.

Supposing a sealing cap to be held by the magnet within the cavity *f* in the enlargement of the stem 9, and a bottle to be standing on the seat 23, the sealing operation consists in pressing down the treadle 5 which causes the sealing head to descend and the sealing cap to be placed on the bottle head 25 which in Fig. 4 is denoted by B. When the joint-forming gasket is fully compressed in the sealing cap, further downward movement of the stem 9 is suspended, but the descent of the tubular block 3 carrying the annulus 10 with its stems 20 continues, its movement being opposed only by the spiral spring 15 which is further compressed. In this secondary operation of the machine, the heads *j* of the stems 20 engage with the ends 30 of the bolts 19 which are forced inward and their points made to indent the skirt of the cap directly under the shoulder of the bottle head, as shown in Fig. 4. Upon the release of the treadle, the indenting bolts 19 will 35 leave the cap, and as soon as the spring 15 has expanded to its original length, the stem 9 will rise leaving the sealed bottle on the seat 23.

Owing to stems 20 being backed by the 45 springs 21 the pressure exerted on the bottle head by the indentation of the skirt of the cap can never be greater than that due to the strength of the said springs; and in the construction of the machine such springs are 50 selected as will yield when the required force to properly seal the bottle is reached, and the breakage of bottles thereby prevented.

It will be understood that as the indenting bolts 19 operate independently of each other, 55 irregularities in form of the bottle head do not affect the sealing operation, the indentations being deeper or shallower according to the shape of the bottle head at the particular point against which the skirt of the cap is 60 pressed.

The sealing cap, shown in Fig. 4, corre-

sponds in construction with a cap described and claimed by me in my application for Letters Patent filed on the 13th day of September, 1907, under Serial Number 392,702, but 65 the present invention may be used in connection with any other construction of cap where the diameter of the cap has to be reduced to bring a portion of the skirt of the same closely under the shoulder of the bottle head in a 70 bottle sealing operation.

I claim as my invention,—

1. In a machine for sealing bottles, a sealing head having a cavity for the reception of a sealing cap and a system of independently- 75 acting spring-held bolts which surround the said cavity and are adapted to enter the same, combined with a system of spring-held stems placed exteriorly of the said bolts, and means whereby the said stems may be brought 80 into contact with the ends of the said bolts and thereby force their points into the said cavity, substantially as, and for the purpose specified.

2. In a machine for sealing bottles a sealing head in which are combined a tubular block carrying an annulus having a conical inner surface with a system of inclined spring-held stems circumferentially arranged within its wall, a spring-held stem situated 85 within the tubular block, with a cap cavity at its end, and a system of cap-indenting bolts within the wall surrounding the cavity which are normally below and in vertical alinement with the said stems, and adapted 90 to be brought into contact with the same, substantially as, and for the purpose specified.

3. In a machine for sealing bottles, a sealing head in which are combined the following elements: a tubular block having at its 100 lower end an annulus carrying a system of independent spring-held stems which are arranged around the inner circumference of the annulus and project within the same, a spring-held stem situated within the tubular 105 block, having a cap cavity at its end, a system of bolts which penetrate the wall which surrounds the cap cavity and are in vertical alinement with the said stems, and mechanism to yieldingly hold the points of the bolts 110 practically within the said wall, the said tubular block with its spring-held stems being adapted for downward movement independently of the spring-held bolts, when the said stems will engage with the outer ends of the 115 spring-held bolts and thereby force their inner ends or points into the cap cavity, substantially as, and for the purpose specified.

EMORY J. GODMAN.
